FIG. 1

FIG. 2

FIG. 3

INVENTOR.

Ernest J. Sweetland

UNITED STATES PATENT OFFICE

118,730

DESIGN FOR A COMBINED WARMING AND DRYING APPARATUS

Ernest J. Sweetland, Piedmont, Calif.

Application February 4, 1939, Serial No. 82,778

Term of patent 14 years

To all whom it may concern:

Be it known that I, Ernest J. Sweetland, a citizen of the United States and a resident of the city of Piedmont, county of Alameda, State of California, have invented a new, original, and ornamental Design for a Combined Warming and Drying Apparatus, of which the following is a specification, reference being had to the accompanying drawing, forming part thereof.

Figure 1 is a rear elevational view of a combined warming and drying apparatus showing my new design;

Figure 2 is a side elevational, and

Figure 3 is a front elevational view thereof.

I claim:

The ornamental design for a combined warming and drying apparatus, substantially as shown.

ERNEST J. SWEETLAND.
